NOTE PAPER DISPENSER

Donald A. Hillis, 27 Kingslake Road,
Willowdale, Ontario, Canada

Filed Oct. 23, 1967, Ser. No. 9,104

Term of patent 14 years

Int. Cl. D19—02

U.S. Cl. D74—1

FIG. 1 is a front and right side perspective view of the note paper dispenser showing my new design, the left side being a mirror image thereof; and

FIG. 2 is a rear and right side perspective view of the note paper dispenser shown in FIG. 1.

I claim:

The ornamental design for a note paper dispenser, as shown and described.
